H. E. MACCAMY,
CONDENSER AND COOLER,
APPLICATION FILED JUNE 3, 1920. RENEWED JUNE 3, 1922.

1,427,611.

Patented Aug. 29, 1922.

UNITED STATES PATENT OFFICE.

HARRY EDWIN MACCAMY, OF LOS ANGELES, CALIFORNIA, ASSIGNOR TO SOUTHWESTERN CONDENSER COMPANY, OF LOS ANGELES, CALIFORNIA, A CORPORATION OF CALIFORNIA.

CONDENSER AND COOLER.

1,427,611.

Specification of Letters Patent. Patented Aug. 29, 1922.

Application filed June 3, 1920, Serial No. 386,332. Renewed June 3, 1922. Serial No. 565,744.

To all whom it may concern:

Be it known that I, HARRY EDWIN MACCAMY, a citizen of the United States, residing at Los Angeles, in the county of 5 Los Angeles and State of California, have invented a new and useful Condenser and Cooler, of which the following is a specification.

This invention relates to devices for condensing and cooling substances passing through the device.

One of the objects of this invention is to cool the body of the device thereby facilitating the operation of the device.

Another object is to cool the body of the device in conjunction with and by the cooling system of the device for facilitating a cooling and condensing of the matter passing through the device.

Another object is to provide a device of this type with double walls for keeping the inner condensing walls in a condition similar to that of the condensing tubes in the device.

Another object is to increase the efficiency of devices of this type.

Another object is to provide a number of individual cooling units, independently receiving and discharging a cooling medium so that the efficiency of the several individual units can be equally well controlled.

Another object is to provide a number of individual cooling units, so that any of the units may be repaired or cleaned without impairing the efficiency of the other units.

Another object is to provide a suitable number of cooling units, each of the units receiving and discharging a cooling medium independently of the others so that the passing matter to be cooled meets constantly and continuously freshly cooled surfaces so as to insure very rapid condensation and cooling, which makes it possible to obtain a high degree of vacuum with the minimum amount of cooling medium.

Another object is to provide tube plates into which all cooling tubes are equally well sealed independently of the body of the device.

Another object is to provide a number of closing plates so as to cover the ends of different units of cooling tubes, such plates being provided with return pockets for allowing the cooling medium from one tube to

pass over to and through the nearest next tube.

Other objects will appear from the following description and appended claims as well as from the accompanying drawing, in which—

Fig. 1 is a front elevation of the device, one cover plate being removed and a portion being broken away to show inside construction and details.

Fig. 2 is a side elevation of the device.

Fig. 3 is a horizontal cross section of the device on line 3—3 of Fig. 1.

Fig. 4 is a fragmentary detail midsectional view of one end of a cooling tube as secured within the tube plate.

Fig. 5 is a fragmentary sectional illustration of body, tube plate, and cover plate, held together by a common bolt, the tube plate independently to the body and the cover plate also independently to the body outside of the tube plate.

Fig. 6 is a fragmentary sectional illustration of tube plate and cover plate connected by a short stud bolt.

Fig. 7 is a fragmentary illustration in which the outlet tubes or the outlets of the device are arranged to communicate with a single common outlet tube 26, instead of the two outlet tubes 26 shown in Fig. 3, showing that the outlets of the several tube units may (just as well as the inlets) be connected to one common main tube.

The walls of the main body 5 of the device are provided with a number of cooling chambers 6. These chambers are provided with communicating conduits or openings 7, 8, 9, 10, 11 and 12. An inlet tube 13 communicates with the upper chamber. An outlet tube 14 communicates with the lowermost chamber. By this arrangement, a cooling medium can be directed through the tube 13 into the uppermost chamber, and, by passing from the uppermost chamber through the opening 7 into the next lower chamber and from the second chamber through the opening 8 into the third chamber and so on from chamber to chamber through the several openings 9, 10, 11 and 12, such medium can be caused to circulate through the several chambers downward to pass out through the outlet tube 14. It will easily be understood. In the drawing, two series or sets of chambers 6 and com-

municating openings 7, 8, 9, 10, 11 and 12 are shown to be in the opposite side walls of the body, each set of communicating chambers having an inlet 13 and an outlet 14; 5 but it will easily be understood that such chambers 6 can be arranged slightly modified to be controlled by more or eventually less inlet and outlet tubes, without materially departing from the principle of this 10 invention.

The front and rear sides of this main body are open. These sides are normally covered by the tube plates 15. The several cooling tubes 16 are individually expanded and eventually beaded so as to firmly engage with the tube plates 15 at the rear and front sides of the device as illustrated in detail in Fig. 4 15 at 17. When so firmly engaged with the tube plates 15, the tubes naturally are disposed within the body arranged in the desired manner.

End or cover plates 18 are provided to close or suitably cover the open ends of the tubes. Such plates 18 are provided with return pockets 19, arranged in such a manner in the closing surface of the plates that a suitable number of tubes can communicate in a consecutive manner so as to make such 20 number of tubes an independent unit. The 25 sectional illustration of Fig. 3 is so arranged, according to the section line 3—3 in Fig. 1, as to bring out that the two units have each a separate inlet and outlet; in Fig. 1, the units being illustrated as having 30 and occupying three rows of pipes, one row of pipes above another row of pipes, four pipes in a row in a unit; but it will easily be understood that the number of pipes illustrated in the drawing have only been 35 chosen to make the device appear clearly in the drawing, that, however, more pipes can be in a row, and more rows can be in a unit. The cooling medium is in this manner directed and passed into one pipe in one row 40 to pass in a consecutive manner through the several pipes in that row and the following rows of that unit to finally pass out of another pipe in the last row in that unit, as will more clearly be described later on. 45 Connecting ends 20 are provided on one cover plate to form the inlet, see Fig. 3 in connection with Fig. 2. Connecting ends 21 are provided in the same cover plate to form the outlet. Such inlets and outlets are arranged so as to come into alignment with one of the tubes ever so often as can clearly 50 be seen in Figs. 1, 2 and 3. In Fig. 1, the tube indicated at 22 is in alignment with one of such inlets in the cover plate, and the 55 tube 23 is in alignment with one of the outlets, so that all the tubes between the points 22 and 23, designated by the numeral 24, form one independent unit, the several tubes 60 65 in this unit 24 communicating through the return pockets 19 in the cover plates 18.

The cooling medium passes through this unit from the inlet 20, see Fig. 3; through the tube indicated at 22 in Fig. 1 towards the front of the device; through the return pocket 19 in the front cover plate over to 70 the second tube of the unit, see Fig. 3; through the second tube in the lower row of this unit towards the rear; through the return pocket 19 in the rear cover plate 18 over to the third tube in the lower row of 75 that unit; through the third tube in the lower row towards the front; through the return pocket 19 in the front cover plate 18 over to the fourth tube of the lower row; through the fourth tube towards the rear; 80 through the return pocket in the rear cover plate over to the fourth tube in the row above the row of tubes just referred to; through the four tubes in this second row, and through the return pockets in the front 85 and rear cover plates in a similar manner as described with reference to the first row; through the return pocket in the rear cover plate over to the first tube in the row above the row of tubes just referred to; through 90 the four tubes in this third row of tubes, and through the return pockets in the front and rear cover plates in a similar manner as described with reference to the first row of tubes; and from the fourth tube in this third 95 row of tubes out through the outlet 21, see Fig. 3; the tube indicated at 22 in Fig. 1 communicating with the inlet 20, indicated in Fig. 3; and the tube indicated at 23 in Fig. 1 communicating with the outlet 21, indicated in Fig. 3.

All the inlets are preferably connected to a common inlet tube 25, and all the outlets are preferably connected to a common outlet tube 26. In the drawing there being shown two such outlet tubes 26, since the outlets are illustrated further apart, but, of course, the outlets too may and can be arranged with similar bends as illustrated on the inlets so that one common outlet tube can be used to 100 receive connections from all outlets, as will easily be understood from the fragmentary illustration in Fig. 7 without further illustration and explanation.

Each outlet and inlet connection is preferably provided with an individual valve 27 so that each such connection can be shut off from the common inlet and outlet tubes. Between the valves on the one side and the inlets and the outlets on the other side, 110 proper union connections must, of course, be provided so that the cover plates can be removed from between the valves and the main body, as will also easily be understood without further detail illustration and explanation.

Screening or current breaking plates 28 are preferably disposed over the top unit and between the several units for breaking up the passing substances, as vapors and 130

other substances passed through the device for cooling and condensing purposes, and to further facilitate the operation of the device. Such plates 28 are normally of plain sheet metal and are perforated to allow the passing of such substances through the device.

Any substances to be treated in the device are passed in at 29 and discharged at 30, so that such substances have to pass through the several perforated plates 28 and around the several tubes 16 in the several units.

When the device is being used for cooling and condensing purposes, the matter to be cooled passing through the device from end 29 to end 30, a cooling medium must naturally be passed through the tubes 16 in the path of the matter to be cooled.

It is very common that a device of this type becomes leaky, or that one or another of the tubes becomes defective or clogged up. To overcome such defects in devices of this type, and to avoid a putting out of commission of the whole device, the cooling tubes 25 are arranged in units, and the units are arranged so that any of the units may be inspected without influencing the other units during the operation of the device, as described above.

30 The bolts 31 are provided to hold the whole device together, that is to secure the tube sheets 15 and the cover plates 18 to the side walls. For properly sealing up the device, and, since the individual cover plates 35 18 are to be removed one independently of the other, to make a good water and vapor-tight device even during the time when one or the other of the cover plates is removed, it is naturally necessary that some of the bolts 31 be used for sealing and securing the tube sheets to the body, as indicated at 35 in Fig. 2, while other bolts are provided for the holding of the cover plates alone, as indicated at 36. Such bolts can, however, be

45 modified in quite a number of slightly different forms. One form is illustrated in Fig. 5, the bolt 37 being provided with shoulder-members 38 for separately securing the tube sheets to the body and receiving the cover plates outside of the shoulder member to be held by extra nuts 39. Such slight differences in the arrangements are of course immaterial and only a matter of convenience in assembling the device, and, since 50 that kind of stud-bolts are known in so many different shapes and designs to any mechanic, such fastening, securing and assembling as well as taking apart will be understood without further detail illustration and explanation of specific forms of bolts. The bolts 32 are illustrated in Fig. 3 as passing through the whole device for holding the outside cover plates. This also will be understood not to be necessary since

55 within the tube sheets to allow a securing of the cover plates to the tube sheets by such short stud-bolts as illustrated in Fig. 6. Other minor detail parts are not illustrated since all are well known to any mechanic, and, since no detail claim of such minor connecting parts are made, this specification will be sufficient to make this application understood to any one interested in devices of this kind.

75 It will also easily be understood that slight modifications can be arranged without departing from the spirit of this invention and that I do not wish to limit myself to the specific construction as illustrated in 80 the drawing, but only to matter as far as claimed.

Having thus described my invention, I claim:

1. In a device of the class described, a 85 plurality of units comprising a body having a passage therethrough, tubes disposed crosswise through the passage in the body, cover plates having a number of return pockets to form end communications between adjacent 90 tubes and having a number of inlets and outlets each pair of inlets and outlets, embracing a number of return pockets so as to form a tube unit between each pair of inlets and outlets, means whereby the several units 95 may be connected in parallel to common inlet and outlet manifolds, and independent means for controlling the flow of cooling fluid through each unit.

2. In a device of the class described, a 100 body having a passage therethrough and having cooling chambers within its walls, and cooling tubes disposed crosswise through the passage in the body and having outside connections for independently passing a cooling medium through certain numbers of the tubes.

3. In a device of the class described, a body having a passage therethrough, tubes disposed crosswise through the passage in 110 the body, cover plates having a number of return pockets to form end communications between adjacent tubes and having a number of inlets and outlets, an inlet and an outlet embracing a number of return pockets 115 so as to form a tube unit between each said pair, each unit having independent outside inlet and outlet connections, an inlet manifold connected with the several inlet connections of the several units, an outlet manifold 120 having communication with the several outlet connections of the several units, tube sheets between the cover plates and the body supporting the several tube ends.

4. In a device of the class described, a 125 body having a passage therethrough, tubes disposed crosswise through the passage in the body, cover plates having a number of return pockets to form end communications between adjacent tubes and having a number 130

of inlets and outlets, an inlet and an outlet embracing a number of return pockets so as to form a tube unit between each said pair, each unit having independent inlet and outlet connections outside of the body, an inlet manifold having communication with the several inlet connections of the several units, an outlet manifold having communication with the several outlet connections of the several units, means for controlling the inlet from the inlet manifold independently for each unit, means for controlling the outlet to the outlet manifold independently for

each unit, tube sheets between the cover plates and the body for supporting the several tube ends, and perforated plates disposed in the passage of the body and between the several units.

In testimony that I claim the foregoing as my invention I have signed my name in the presence of two subscribing witnesses.

HARRY EDWIN MACCAMY.
